UNITED STATES PATENT OFFICE.

OTTO H. BOGER, OF CHICAGO, ILLINOIS.

WINDOW-GUARD.

1,055,127.

Specification of Letters Patent.

Patented Mar. 4, 1913.

Application filed September 5, 1911. Serial No. 647,528.

To all whom it may concern:

Be it known that I, OTTO H. BOGER, a citizen of the United States, residing at Chicago, in the county of Cook and State 5 of Illinois, have invented new and useful Improvements in Window-Guards, of which the following is a specification, reference being had to the accompanying drawings, forming a part thereof.

10 The purpose of this invention is to provide an improved construction of guard for windows, adapted both to prevent accidental falling through the open window and also as a protection against unauthorized 15 entrance when the window is open for ventilation.

It consists of the elements and features of construction shown and described as indicated in the claims.

20 In the drawings:—Figure 1 is an inner side elevation of a window equipped with this invention. Fig. 2 is a horizontal section of the window and guard, showing the guard in process of insertion. Fig. 3 is an 25 enlarged detail section at the line, 3—3, on Fig. 1. Fig. 4 is an enlarged detail section at line 4—4 on Fig. 1. Fig. 5 is a detail section at the line, 5—5, on Fig. 1, on an enlarged scale. Fig. 6 is a detail section at 30 line 6—6 on Fig. 3. Fig. 7 shows a form of reinforcing escutcheon plate suitable for use in this device.

In the drawings, 1 represents the upper 35 side bars of the window casing which is provided with sockets, 2, bored into the casing in the lower part of the run-way of the upper sash, which are furnished with reinforcing surface plates or escutcheons, 4—4, set in flush with the casing so as not to interfere with the running of the sash thereon. The guard device is designed to be inserted 40 between the stops, 5—5, in the lower part of the run-way of the upper sash, and to be of such height as to make it impossible to 45 lower the upper sash more than a few inches so that when the guard is in place, the upper sash cannot be opened enough to admit an intruder. The guard comprises two members, A and B, each composed of two or 50 more horizontal bars, 7, 7, only two being shown in the drawings, the number being determined by the height of the opening to

be guarded, and vertical rods, 9,—9, extending through the horizontal rods and rigid therewith at their junctions. The horizontal bars, 8,—8, of the two guards are constructed to lap each other a sufficient distance so that the ends of the horizontal bars of one section are pivoted upon a vertical rod of the opposite section which is located 55 back from the inner ends of the horizontal bars of that section a distance substantially equal to the desired interval between the consecutive vertical rods. Holes, 10,—10, are provided in the horizontal bars of both 60 sections at the position such that the said holes in the bars of one section coincide with the holes in said bars of the other section when the two sections are in line with each other, that is, in the same plane. The outer 65 ends of the horizontal bars outside the outermost of the vertical rods, terminate in slightly curved hooks, 12, which are positioned to enter the sockets, 2, through the escutcheons or reinforcing plates, 4—4, the 70 curvature of the hooks being such as to adapt them to enter and to follow in through the holes in the escutcheon plates, as the two guards pivoting about their connecting vertical rod are straightened from 75 the position shown in Fig. 2, to the closed position in which they are alined, or in the same plane. In order to render the corresponding bars, 7, of the two members, A, and B, comparatively rigid with each other 80 with respect to upward and downward bending, the lapped ends of the two bars are provided with angular rods, 21, turned upon each bar so as to engage the lapped portion of the other bar when they are alined with 85 each other. For securing the two members, A, B, in said closed position, there are provided two locking rods, 15 and 16, which together are adapted to constitute an additional vertical rod for guarding the aperture. The upper of these rods has at a short 90 distance above its lower end an inwardly-projecting lug, 16^a, whose lower face is at right angles to the length of the rod, and on the lower rod, 15, there is mounted a 95 sleeve, 17, having at its upper end a corresponding lug, 17^a, the two lugs, 16^a and 17^a, having apertures, 16^b and 17^b, adapted to register and receive the shackle of a pad lock, 100

18, for securing them together. It will be observed that the sleeve, 17, when moved up to bring its lug, 17^a, against the lug, 16^a, incloses the meeting ends of the two rods, 5 rendering them rigid as against any bending action. At the portion of the rods, 15 and 16, at which they respectively pass through the bars, 7, they are swaged to form a squared portion, 19, and immediately inward therefrom,—that is, below the 10 squared portion of the upper rod and above the squared portion of the lower rod, stop flanges, 20, which stop against the bars, 7, respectively, and the holes, 10, in said bars are made square to receive said portions of 15 the squared rods, respectively.

When the two members, A and B, are brought into closed position, that is, alined in one plane so that the square apertures, 20, of their respective bars coincide, the lower rod, 15, is inserted through the coinciding square apertures of the lower bars down to the shoulder, 20, and this rod has its said squared end adapted to fit quite 25 tightly in said square apertures of the lower bars. The upper rod, 16, is then similarly inserted up through the square apertures of the upper bars, its squared end being adapted to fit a little loosely thereon so that 30 it may be thus inserted, although necessarily deflected slightly out of line with the apertures in order to slide by the upper end of a previously inserted lower rod.

The aggregate distance at the outer 35 faces of the stopped flanges or shoulders, 20, from the meeting ends of the rods, 15, and 16, respectively, is substantially the distance between the upper and lower bars, 7—7, of the frame, A, whose bars fitting between 40 the corresponding upper and lower bars of the frame, B. When, therefore, the upper rod, 16, is pushed up through the square opening up to the upper bars, until it can be moved over at the lower end into line 45 with the lower rod and the sleeve, 17, is moved up to embrace the meeting end of both rods and bring its lug, 17^a, into position for registering the apertures of the two lugs, 16^a, and 17^a, so that the pad-lock 50 shackle can be inserted through them. The two bars are quite tightly stopped by their stop flanges, 20, between the bars, 7—7, and longitudinal movement up or down is prevented so long as the pad lock holds them 55 engaged. With the parts in this position, it will be seen that the two members, A and B, are positively locked against folding outward or so as to be disengaged from the window casing.

60 I claim:—

1. A window guard comprising two members vertically hinged together for folding, adapted to be adjusted alined in one plane, said members each comprising upper and 65 lower horizontal bars and vertical rods in-

tersecting the bars and being hinged together by pivotal connection of bars of one member upon one of the rods of the other member, the upper and lower bars of said two members having apertures which when 70 the bars are alined are intermediate the proximate vertical rods of the two members; locking rods adapted to be inserted through such coinciding apertures to hold the two members alined, said locking rods 75 engaging, one with the upper bars and the other with the lower bars, and having at their meeting ends intermediate the bars, means for connecting them and holding them in alinement with each other. 80

2. A window guard comprising two members vertically hinged together for folding, adapted to be adjusted alined in one plane, said members each comprising upper and lower horizontal bars and vertical rods intersecting the bars and being hinged together by pivotal connection of bars of one member upon one of the rods of the other member, the upper and lower bars of said two members having apertures which when 85 the bars are alined are intermediate the proximate vertical rods of the two members; locking rods adapted to be inserted through such coinciding apertures to hold the two members alined, said locking rods 90 engaging, one with the upper bars and the other with the lower bars, a sleeve on one of said rods adapted to be moved to engage the meeting end of the other rod, said sleeve at one end and said other rod having 95 respectively, laterally-projecting lugs which encounter each other to stop the sleeve, said lug being apertured to receive the shackle of a pad-lock for locking them together to hold the sleeve in engagement with both 100 rods. 105

3. A window guard comprising two members vertically hinged together for folding, adapted to be adjusted alined in one plane, said members each comprising upper and lower horizontal bars and vertical rods intersecting the bars and being hinged together by pivotal connection of the bars of one member upon one of the rods of the other member, the upper and lower bars of 110 said two members having apertures which when the bars are alined are intermediate the proximate vertical rods of the two members; locking rods adapted to be inserted through such coinciding apertures to hold the two members alined, said locking rods 115 engaging, one with the upper bars and the other with the lower bars, a sleeve on one of said rods adapted to be moved to engage the meeting end of the other rod, said sleeve at 120 125 one end and said other rod having respectively, inwardly-projecting lugs which encounter each other to stop the sleeve, said lugs being apertured to receive the shackle of a pad-lock for locking them together to 130

hold the sleeve in engagement with both rods, said locking rods being squared at the portions thereof which pass through said bars and the hole in said bars being square to fit the squared portion of the rods for holding the pad-lock receiving lugs at the inner side.

In testimony whereof, I have hereunto set my hand at Chicago, Cook county, Illinois this 21st day of August 1911.

OTTO H. BOGER.
